CLAIM

The ornamental design for a lightning preventer air terminal, as shown and described.

DESCRIPTION

FIG. 1 is a perspective view of a lightning preventer air terminal showing a preferred embodiment of my new design;

FIG. 2 is a side elevational view thereof, the opposite sides being a mirror image;

FIG. 3 is a top plan view thereof; and

FIG. 4 is a bottom plan view thereof;

FIG. 5 is a perspective view of a lightning preventer air terminal showing a further embodiment of my new design;

FIG. 6 is a side elevational view thereof, the opposite sides being a mirror image;

FIG. 7 is a top plan view thereof; and,

FIG. 8 is a bottom plan view thereof.

FIGS. 1 and 5 have been drawn on enlarged scale with respect to the remaining figures.
